UNITED STATES PATENT OFFICE

102,901

DESIGN FOR A SHOE

Morris Kalmon, St. Louis, Mo.

Application December 5, 1936, Serial No. 66,352

Term of patent 3½ years

To all whom it may concern:

Be it known that I, Morris Kalmon, a citizen of the United States, residing at St. Louis, Missouri, have invented a new, original, and ornamental Design for Shoes, of which the following is a specification, reference being had to the accompanying drawing, forming part thereof.

Figure 2 is a side perspective view of the same, showing my new design, the shoe being tilted slightly towards the point of view to illustrate more clearly its appearance.

I claim:

The ornamental design for a shoe substantially as shown and described.

MORRIS KALMON.
